UNITED STATES PATENT OFFICE.

MICAJAH B. HELLER, OF WESTMINSTER, SOUTH CAROLINA.

PLOW.

1,331,502.

Specification of Letters Patent.

Patented Feb. 24, 1920.

Application filed November 10, 1919. Serial No. 336,902.

To all whom it may concern:

Be it known that I, MICAJAH B. HELLER, a citizen of the United States, residing at Westminster, in the county of Oconee and 5 State of South Carolina, have invented new and useful Improvements in Plows, of which the following is a specification.

This invention relates to plows and it has particular reference to plows in which the 10 blade carrying standard is pivotally mounted on the beam so as to be capable of being angularly adjusted with respect to the beam.

The invention has for its object to provide a device of simple and improved construction 5 whereby the standard may be angularly adjusted and securely retained or locked in various adjusted positions.

With these and other ends in view which 20 will readily appear as the nature of the invention is better understood, the same consists in the improved construction and novel arrangement and combination of parts which will be hereinafter fully described and particularly pointed out in the claims.

25 In the accompanying drawing has been illustrated a simple and preferred form of the invention, it being, however, understood that no limitation is necessarily made to the precise structural details therein exhibited, 30 but that changes, alterations and modifications within the scope of the claims may be resorted to when desired.

In the drawing,

Figure 1 is a side elevation of a plow constructed in accordance with the invention.

Fig. 2 is a top plan view of the same.

Fig. 3 is a side elevation of the plow as seen from the opposite side, and the standard having been adjusted to a different position.

40 Fig. 4 is a vertical transverse sectional view taken on the line 4—4 in Fig. 1.

Corresponding parts in the several figures are denoted by like characters of reference. 45 The standard 15 which is of the well known U-shaped or bifurcated type is pivotally mounted on the plow beam 16 by means of a bolt or pivot member 17 the standard being provided with forwardly extending 50 arms 18 having terminal cheeks 19, provided with a row of perforations 20 arranged in vertical series for the passage of transverse connecting bolts or pivot members.

55 Secured upon and extending outwardly from the beam 16 is a rack bar 22 the toothed edge of which faces in a rearward direction.

While this rack bar may be constructed and secured in various ways it is preferred to form the same as a part of a casting which also includes a base or foot-piece 23, the same 60 being apertured for the passage of fastening members such as screws 24. By this construction the rack bar may be secured on the plow beam without materially weakening the latter which is an important considera- 65

Pivots connected with the cheeks 19 by means of bolts or connecting members 25 is a yoke 26 which extends upwardly, straddling the beam, said yoke being so arranged 70 and proportioned that the bridge portion thereof may engage in one of the notches 27 of the rack bar 22. A coiled spring 28 connects the yoke 26 with the beam 16, the tension of said spring being exerted to swing 75 the yoke in the direction of the rack bar for engagement therewith. Riveted upon or otherwise suitably connected with the yoke 26 is the handle 29 whereby the yoke may be conveniently retracted from engagement 80 with the rack bar against the tension of the spring 28.

It will be readily seen that when the yoke 26 is disengaged from the rack bar 22, the standard 15 and the beam 16 may be relatively moved about the axis of the pivot member 17, thus enabling any desired angular adjustment of the standard with respect to the beam to be effected. When the desired adjustment has been made and the 90 operator releases the handle 29, the yoke, under the tension of the spring 28 will be moved in engagement with the rack bar and the parts will thus be securely held in the desired adjusted position.

95 It will be observed that the yoke 26 which straddles the beam not only constitutes what may be termed a dog for engagement with the rack bar, the said bar constituting also a brace or connecting member for the forwardly extending arms of the standard, reinforcing the same as against lateral or outward displacement, enabling the arms of the standard to be made lighter and less expensive than would otherwise be the case. It 100 will also be noticed that the limbs of the yoke are to be of such a length as to enable the said yoke to be adjusted with respect to the cheeks 19 having the rows of perforations 20, raising or lowering the yoke with 110 respect to the cheeks, and thereby materially increasing the range of adjustment.

Having thus described the invention, what is claimed as new is:

1. A plow beam, a standard pivoted thereon and having a forwardly extending arm 5 provided with a cheek piece having a vertical series of apertures, a rack bar extending upwardly from the plow beam, a rack engaging member pivotally connected with the cheek, and a spring connecting the rack 10 engaging member with the plow beam to force it in the direction of the rack.
2. A plow beam, a standard pivoted thereon and having forwardly extending arms provided with cheeks adjacent to the side 15 faces of the beam, a rack bar extending upwardly from the beam, a yoke pivotally connected with the cheeks, said yoke straddling the beam and engaging the rack bar, and a spring whereby the yoke is forced in the direction of the rack bar. 20
3. A plow beam, a standard pivoted thereon and having forwardly extending arms provided with cheeks adjacent to the side faces of the beam, a rack bar extending upwardly from the beam, a yoke pivotally connected with the cheeks, said yoke straddling the beam and engaging the rack bar, and a spring whereby the yoke is forced in the direction of the rack bar, said yoke being 25 provided with an upwardly extending handle whereby it may be conveniently manipulated against the tension of the spring. 30

4. A plow beam, a standard pivoted thereon and having forwardly extending arms provided with terminal cheeks adjacent to 35 the sides of the plow beam, each cheek being provided with a plurality of perforations arranged in vertical series, a rack bar extending upwardly from the plow beam, a yoke adjustably connected with the cheeks 40 by pivot members engaging some of the perforations therein, said yoke straddling the beam, and a spring whereby the yoke is forced in the direction of the rack bar for engagement therewith. 45

5. A plow beam, a standard pivoted thereon and having forwardly extending arms provided with terminal cheeks adjacent to the sides of the plow beam, each cheek being provided with a plurality of perforations 50 arranged in vertical series, a rack bar extending upwardly from the plow beam, a yoke adjustably connected with the cheeks by pivot members engaging some of the perforations therein, said yoke straddling the 55 beam, and a spring whereby the yoke is forced in the direction of the rack bar for engagement therewith, said rack bar having a foot piece provided with apertures for the passage of fastening members whereby 60 it is secured on the beam.

In testimony whereof I affix my signature.

MICAJAH B. HELLER.
